UNITED STATES PATENT OFFICE.

JOHN B. NEIL, OF NEW YORK, N. Y., ASSIGNOR TO THE BIGELOW CARPET COMPANY, OF CLINTON, MASSACHUSETTS.

DESIGN FOR CARPET.

SPECIFICATION forming part of Design No. 12,247, dated May 3, 1881.

Application filed February 8, 1881. Term of patent 3½ years.

To all whom it may concern:

Be it known that I, JOHN B. NEIL, of New York, in the county and State of New York, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

D is a stripe, ornamented with a rectangular pattern, running parallel or adjacent to the stripe E, which last contains figures a, resembling arrow-heads, and between two bands, each containing a series of overlapping triangles. The stripe E contains, also, a portion of the figure n.

H is a stripe having a patterned background and containing the group F, containing figure k, composed of leaves b, and of roses and surrounding foliage, and also containing the figure n, a projecting spray which runs into the stripe E, and also the spray m, bearing leaves and flowers. The stripe H also has on it the group B, containing figure p, made up of roses and foliage, and the figure h—a projecting spray bearing circular flowers. The patterned stripe C, ornamented with a series of triangular fig-

ures each slightly overlapping the one next to it, borders on the stripe H.

I claim—

1. The design for carpets, consisting of the stripe D, substantially as shown. 35
2. The design for carpets, consisting of the stripe E, containing figures a and a portion of figure n, substantially as shown.
3. The design for carpets, consisting of the group F, containing figures k, b, m, and n, substantially as shown. 40
4. The design for carpets, consisting of the figure p, substantially as shown.
5. The design for carpets, consisting of the group B, containing figures p and h, substantially as shown. 45
6. The design for carpets, consisting of the stripe H, containing figures k b n m h, substantially as shown.
7. The design for carpets, consisting of the stripe C, substantially as shown. 50
8. The design for carpets, consisting of the stripes D and E, substantially as shown.
9. The design for carpets, consisting of the stripe D, stripe E, stripe H, containing figures k b n m p h, and stripe C, substantially as shown. 55
